FULL AUTOMATIC PISTOL

Horace J. Kennedy, Hartford, Conn., assignor to
Colt's Manufacturing Company, a corporation
of Connecticut

Application July 28, 1945, Serial No. 607,579

8 Claims. (Cl. 89—140)

1

While the invention in its broader aspects is not so limited, it is particularly applicable to a semi-automatic pistol of otherwise standard design and construction and is more specifically applicable to the pistol officially known as the cal. .45 M1911A1 automatic pistol.

One of the objects of the invention is to provide simple and reliable means under the control of the trigger for repetitively releasing the sear automatically to effect full automatic firing, that is, repetitive firing which will continue so long as the trigger is pressed and cartridges are available in the magazine. More specifically, it is an object of the present invention to provide such means adapted to be readily substituted in a standard cal. .45 M1911A1 automatic pistol with a minimum of changes in the standard pistol parts.

A further object of the invention is to provide means for effecting full automatic operation of the pistol as described, such means, however, being optionally usable so that, when not used, the pistol may operate as a semi-automatic pistol, firing only one shot for each movement of the trigger. More specifically, it is an object of the invention to attain such results by the substitution of parts in a standard cal. .45 M1911A1 automatic pistol with a minimum of changes in the standard pistol parts.

From the specification further objects and advantages of the invention will be apparent to those skilled in the art.

In the accompanying drawings I have shown the embodiment of the invention which I now deem preferable, but it will be understood that the drawings are intended for illustrative purposes only and are not to be relied upon as defining or limiting the scope of the invention, the claims forming a part of this specification being relied upon for that purpose.

In the drawings:

Fig. 1 is a side elevation of a cal. .45 M1911A1 automatic pistol in which the invention may be incorporated.

Fig. 2 is a fragmentary transverse sectional view of the rear portion of the pistol with the invention incorporated therein, this view being taken along the line 2—2 of Fig. 1.

Fig. 3 is a fragmentary longitudinal sectional view taken along the line 3—3 of Fig. 2, this view showing the slide forward and the hammer in cocked position.

Fig. 4 is a view similar to Fig. 3 but showing the parts in the positions which they occupy immediately after firing, the slide having started

2

in the rearward direction to effect recocking of the hammer.

Fig. 5 is a fragmentary longitudinal sectional view taken along the line 5—5 of Fig. 2, this view showing the slide forward and the hammer in cocked position.

Fig. 6 is a view similar to Fig. 5 but showing the parts in the same relative positions as in Fig. 4.

Fig. 7 is a view similar to Fig. 5 but showing the slide rearward of its forward position and moving in the forward direction.

Fig. 8 is an exploded perspective view showing the sear, the member for moving the sear to effect full automatic operation, and the disconnector.

Fig. 9 is a perspective view of the firing pin stop.

Fig. 10 is a perspective view of an alternative firing pin stop adapted to be used when full automatic operation is not desired.

The drawings show a cal. .45 M1911A1 automatic pistol with certain parts substituted or modified to effect full automatic operation. For details of construction not herein fully shown or described, reference may be had to Patent Nos. 984,519 and 1,070,582.

As shown, the pistol comprises a frame or receiver 11, a barrel 12, a reciprocable slide or breech bolt 13, a firing pin 14, a grip 15, a trigger 16, and a firing member or hammer 17. The grip is adapted to hold a magazine 18 containing a plurality of cartridges which may be successively fed into the chamber of the barrel, fired, and ejected upon operation of the trigger mechanism and automatic reciprocation of the bolt.

The firing pin is slidably mounted in a hole 19 in the bolt and is biased to retracted position by a spring 20 abutting at one end against a shoulder 21 on the firing pin. Rearward movement of the firing pin is limited by a removable stop 22. It is apparent from the drawings, see Fig. 3, that the firing pin is of such length that when the hammer is in its uncocked position, it may rest against the stop 22 without moving the firing pin sufficiently to cause its forward end to project beyond the front face of the bolt portion of the slide 13. When the pistol is intentionally fired the hammer delivers a blow to the rear end of the firing pin and the momentum of the pin causes it to be projected beyond the front face of the bolt to fire the cartridge primer.

The hammer is pivotally mounted in the frame by a pin 23, and is, through a link 24, biased in the clockwise direction by a main spring (not shown). The body of the hammer is bifurcated

and has a shoulder 25 formed thereon, and preferably has a safety, or half cock, recess 26 formed therein. The firing mechanism includes a bifurcated sear 27 pivotally mounted in the frame by a pin 28. The sear is biased in the counter-clockwise direction by a sear spring 29 and is adapted to engage with the shoulder 25 on the hammer to hold the same in cocked position.

A trigger bar 30 is secured to the trigger 16 and is slidably mounted in the frame so as to be movable with the trigger. The trigger bar is shaped to surround the magazine 18. As shown in Fig. 4, the upper edge of the rear end of the trigger bar 30 is positioned to move in a plane below the edge of the lower end of the sear 27.

A pistol embodying the present invention is preferably adapted to operate optionally either as a semi-automatic pistol or a full automatic pistol. The parts necessary for semi-automatic operation will be described first, reference being had particularly to Figs. 2, 3, 4 and 8.

In order that retraction or pressing of the trigger 16 may serve to move and release the sear 27, a member 31 is provided which initially constitutes a connecting means between the trigger bar and the sear. The member 31 also moves to a disconnecting position and will therefore be referred to as a "disconnector." The disconnector 31 is shown more clearly in Fig. 8. The upper end of the disconnector 31 is loosely guided in an aperture in the frame 11 for reciprocatory movement in a direction transverse of the direction of slide reciprocation. The lower portion of the disconnector is positioned between the legs or bifurcations of the bifurcated sear 27, and it has an aperture 32 through which extends the pivot pin 28 for the sear. As this aperture is larger than the pin, the lower portion of the disconnector may move relatively to the frame and sear within limits determined by the size of the aperture. The trigger bar 30 engages directly with the front face of the lower portion of the disconnector.

The lower end of the disconnector 31 is provided with means, such as a lateral projection or wing 33, which is normally adapted to engage with the lower end of the corresponding leg of the sear 27. A spring 34 presses against a cam surface 35 to urge the disconnector upward and in the counter-clockwise direction about a pivotal axis near its upper end in the frame aperture, and inasmuch as the disconnector presses against the trigger bar 30, the latter is thereby biased to its non-firing, or forward, position. The top of the disconnector normally projects above the top of the frame.

When the invention is incorporated in a cal. .45 M1911A1 automatic pistol, the disconnector 31 has the same cooperative size and shape as that portion of a standard disconnector at one side of a vertical longitudinal central plane therethrough. As shown, it corresponds to the portion at the left side, looking forward. In referring to the same "cooperative" size and shape, it is intended to state that those portions which directly cooperate with other parts have the same size and shape, it being obvious however that there may be minor variations in other portions.

As shown in Fig. 3, the projection or wing 33 of the disconnector constitutes a connecting means between the trigger bar 30 and the sear when the disconnector 31 is in the position shown in this figure. When the trigger is pressed, the disconnector is moved transversely of its direction of reciprocation, and the projection 33 en-

gages the sear to move it and release the hammer to effect firing. With the slide in its forward position, the upper end of the disconnector 31 is seated in a recess 36 in the bottom of the slide, and as soon as the slide moves rearward upon recoil the disconnector is forced out of the recess and moved downward. Thus the disconnector is reciprocated by the slide in a direction transverse of the direction of slide reciprocation. When the disconnector is moved downward from the position of Fig. 3 to that of Fig. 4, the projection 33 will no longer be in a position to engage the sear and consequently the trigger can no longer move the sear to, or hold it in, its hammer releasing position. Such downward movement of the disconnector takes places automatically upon each reciprocation of the slide and the gun will operate in a semi-automatic manner. It is clear from Fig. 4 that the projection or wing 33 is below the bottom of the sear and that the disconnector cannot move upward until permitted to do so by releasing the trigger and permitting the trigger bar to move forward. When the trigger is released the disconnector is restored to the position shown in Fig. 3 and firing may be repeated. So far as described up to the present point, the pistol would operate in exactly the same manner as a standard semi-automatic pistol.

Reference will now be made more particularly to Figs. 2, 5, 6, 7, 8 and 9 showing the parts which effect full automatic operation.

A vertically reciprocable member 37 is provided for automatically releasing the sear 27, this member being reciprocated by the slide 13 in a direction transverse of the slide reciprocation. The member 37 is so related to the slide and to the sear that it is moved downward as the slide moves forward and just before the slide reaches its forward breeched position. Downward movement of the member 37 causes it to engage the sear to move it and release the hammer and effect firing.

Preferably and as shown, the member 37 is similar to the disconnector 31 and is similarly positioned and mounted. When the invention is incorporated in a cal. .45 M1911A1 automatic pistol the member 37, except for its lower end portion, has the same cooperative size and shape as that portion of a standard disconnector for the pistol at one side of a vertical longitudinal central plane therethrough, and as shown, it corresponds to the portion at the right side looking forward. The upper end of the member 37 is loosely guided in the same opening in the frame 11 which receives and guides the upper end of the disconnector 31, and the member 37 is also positioned between the legs or bifurcations of the bifurcated sear 27 and it has an aperture 38 through which extends the pivot pin 28 for the sear. As this aperture is larger than the pin, the lower portion of the member 37 may move relatively to the frame and sear within limits determined by the size of the aperture. The trigger bar 30 engages directly with the front face of the lower portion of the member.

The spring 34 which presses against the surface 35 on the disconnector 31 also presses against a cam surface 39 on the member 37 when the trigger 16 is in its non-retracted position to urge the member upward and in the counter-clockwise direction about a pivotal axis near its upper end in the frame aperture. Inasmuch as the member 37 presses against the trigger bar 30 it assists in biasing the latter towards its non-firing or for-

ward position. When the trigger is held in its retracted position, the leg of the spring 34 which presses against the cam surfaces 35 and 39 cannot bias member 37 upward. However, member 37 is biased upward by the leg of spring 34 which engages the sear as the surfaces of the recess 44 and projection 43 function as coacting cam surfaces to move member 37 upward. Alternatively, the disconnector engaging leg of the spring 34 may be bifurcated so that it may act independently on the disconnector 31 and on the member 37.

The upper end of the member 37 is engageable with a cam surface 40 on the slide so as to be reciprocated thereby in a direction transverse of the direction of slide reciprocation. Preferably and as shown, the slide is provided with an additional longitudinal groove 41 into which the upper end of the member 37 may extend. Except for the groove 41, the slide has the same cooperative size and shape as a standard slide. The cam surface 40 is at or near the rear end of the groove 41 and it is formed on a finger or member 42 projecting into the groove 41 and constituting a part of the firing pin stop 22. The cam surface 40 is so located that it engages the member 37 to force it downward as the slide 13 is moving forward and just before it reaches its forward breeched position.

The member 37 has a lateral projection or wing 43 which is at a level above that of the lateral projection or wing 33 on the disconnector 31. With the member 37 in its lower position as shown in Fig. 5, the projection 43 is at the same level as the lower end portion of the right hand bifurcation of the sear 27. Pressing of the trigger with resultant movement of the trigger bar 39 toward the rear, as shown in Fig. 6, causes the lower portion of the member 37, including the projection 43, to move rearward and engage the sear to move it to release the hammer and effect firing.

As soon as firing occurs the slide 13 moves rearward and the member 37 moves upward as shown in Fig. 6, and it will be seen that continued upward movement will carry the projection 43 to a position wherein it is at the same level as a forward opening recess 44 in the right hand bifurcation of the sear 27. Except for the said recess 44, the sear 27 has the same cooperative size and shape as a standard sear. When the projection 43 is opposite the recess, the sear is free to move to reengage the hammer as soon as the hammer reaches its cocked position, as shown in Fig. 7. If pressure is maintained on the trigger to hold the trigger bar 39 in its rearward position, as shown in Fig. 7, the projection 43 is entered into the recess 44. As the slide 13 again moves forward the member 37 is forced downward by the cam surface 40, thus causing the projection 43 to engage the bottom surface of the sear recess 44 to move the sear and release the hammer to effect firing.

From the foregoing description it will be apparent that with the hammer cocked, pressing of the trigger and movement of the trigger bar 39 toward the rear will first move the sear to effect initial firing, and that thereafter so long as the trigger is pressed and so long as a supply of cartridges is available in the magazine, the member 37 will serve to engage and move the sear repetitively to release the hammer upon each reciprocation of the slide. Thus full automatic operation of the pistol is attained, but this can be discontinued at any time by releasing the trigger and

permitting the trigger bar and the lower portion of the member 37 to move forward.

The slide 13 may be rendered inoperative to reciprocate the member 37 when full automatic operation of the pistol is not desired. As shown, this result is attained by removing the firing pin stop 22 with its finger 42 and substituting an alternative firing pin stop 45, which has no finger 42 and which is in fact the standard firing pin stop for the pistol. It will be clear that without the finger 42 and cam surface 40, the upper end of the member 37 will remain in the groove 41 and the member will not reciprocate and will be inoperative.

When the stop 22 and the finger 42 are in place, the disconnector 31 and the member 37 cooperate with each other to effect the initial movement of the sear to release the hammer and effect the initial firing as the projections 33 and 39 simultaneously engage the sear when the trigger is retracted. Otherwise the two members 31 and 37 function entirely independently of each other and when one of them is operative the other is inoperative. They are separately reciprocable by the slide 13 and the disconnector 31 is in its upper position and the member 37 is in its lower position when the slide is in its forward position. As already explained, the disconnector 31 is held in its lower disconnecting position so long as the trigger is pressed and the trigger bar is in its rearward position, as shown in Fig. 4. Thus for full automatic operation the disconnector is entirely inoperative after the initial movement of the sear and the first recoil movement of the slide 13.

If full automatic operation of the pistol is not desired, the stop 22 with the finger 42 is replaced by the standard stop 45, and then the sear operating member 37 remains in its upper inoperative position and firing is effected semi-automatically exactly as in the standard pistol.

If only full automatic operation is desired, and not semi-automatic operation, the disconnector 31 could be entirely omitted, suitable provision being made by means of a filler piece or otherwise for holding the member 37 in its proper location at the right side of the central plane of the pistol.

What I claim is:

- An automatic pistol comprising in combination, a frame, a barrel, a slide automatically reciprocable upon firing, a hammer movable to cocked position by the slide upon recoil movement thereof, a sear for holding the hammer in cocked position and having a cam surface thereon, a trigger, and a member reciprocably mounted in said frame and engageable by the slide for movement thereby and having a cam surface thereon movable to and from a position of engagement with the cam surface on said sear to effect hammer releasing movement of the sear upon reciprocation of said member.

- An automatic pistol comprising a frame, a barrel, a slide automatically reciprocable upon firing, a hammer movable to cocked position by the slide upon recoil movement thereof, a sear for holding the hammer in cocked position and having a cam surface thereon, and a trigger, in combination with a member reciprocably mounted in said frame and engageable by the slide for movement thereby and having a projection thereon including a cam surface movable to and from a position of engagement with said sear to effect hammer releasing movement of the sear upon reciprocation of said member.

3. An automatic pistol comprising in combination, a frame, a barrel, a slide automatically reciprocable longitudinally upon firing, a hammer movable to cocked position by the slide upon recoil movement thereof, a sear for holding the hammer in cocked position and having a cam surface thereon, a longitudinally movable trigger, and a member reciprocably positioned below the slide and movable thereby in a direction transverse of the slide reciprocation, the said member being guided near its upper end to prevent movement longitudinally of the slide and having its lower portion movable by the trigger in the direction of trigger movement, said member having a cam surface thereon which moves into position to engage the cam surface on the sear and release the hammer when the member is moved by pressing the trigger and the said cam surfaces thereafter engaging and moving the sear repetitively to release the hammer upon each reciprocation of the member while the trigger remains in pressed position.

4. An automatic pistol comprising in combination, a frame, a barrel, a slide automatically reciprocable longitudinally upon firing, a hammer movable to cocked position by the slide upon recoil movement thereof, a bifurcated sear for holding the hammer in cocked position and having a cam surface on one of the bifurcations, a pivot pin for the sear, a longitudinally movable trigger, and a member reciprocably positioned below the slide and movable thereby in a direction transverse of the slide reciprocation, the said member being guided near its upper end to prevent movement longitudinally of the slide and having its lower portion movable by the trigger in the direction of trigger movement and the said member having its lower portion extending between the sear bifurcations and having an opening through which the sear pivot pin extends which opening is of suitable size to permit but limit movements of the member, and the said member having a cam surface thereon which moves into position to engage the cam surface on the sear and release the hammer when the member is moved by pressing the trigger and the said cam surfaces thereafter engaging and moving the sear repetitively to release the hammer upon each reciprocation of the member while the trigger remains in pressed position.

5. An automatic pistol comprising in combination, a frame, a barrel, a slide automatically reciprocable longitudinally upon firing and including a removable camming means, a firing pin in the slide, a hammer movable to cocked position by the slide upon recoil movement thereof, a sear for holding the hammer in cocked position and having a cam surface thereon, a longitudinally movable trigger, a member reciprocably positioned below the slide with its upper end adapted to be moved in a direction transverse of the slide reciprocation by engagement of its said upper end with the said camming means, the said member being guided near its upper end to prevent movement longitudinally of the slide and having its lower portion movable by the trigger in the direction of trigger movement, and a cam surface on the said member which moves into position to engage the cam surface on the sear and release the hammer when the member is moved by pressing the trigger and thereafter engaging and moving the sear repetitively to release the hammer upon each reciprocation of the member while the trigger remains in pressed position.

6. In an automatic pistol, the combination of a frame, a barrel, a slide automatically reciprocable upon firing, a hammer movable to cocked position by the slide upon recoil movement thereof, a sear for holding the hammer in cocked position and having a cam surface thereon, a trigger and trigger bar, a disconnector interposed between the trigger bar and the sear when the slide is in breeched position to operatively connect them so that when the trigger is pressed the bar may move the sear to release the hammer, the said disconnector upon recoil movement of the slide being moved thereby to a disconnecting position wherein the sear is free to return to its hammer engaging position independently of the trigger bar, and the said disconnector being restored to its connecting position only upon release of the trigger and upon return of the slide to its breeched position, a reciprocable member having a cam surface thereon separately movable by the slide and engaging the cam surface on the sear repetitively to move the sear and thereby release the hammer without further movement of the trigger.

7. In an automatic pistol, the combination of a frame, a barrel, a slide automatically reciprocable upon firing and including a removable camming means, a hammer movable to cocked position by the slide upon recoil movement thereof, a sear for holding the hammer in cocked position and having a cam surface thereon, a trigger and trigger bar, a disconnector interposed between the trigger bar and the sear when the slide is in breeched position to operatively connect them so that when the trigger is pressed the bar may move the sear to release the hammer, the said disconnector upon recoil movement of the slide being moved thereby to a disconnecting position wherein the sear is free to return to its hammer engaging position independently of the trigger bar, and the said disconnector being restored to its connecting position only upon release of the trigger and upon return of the slide to its breeched position, and a reciprocable member engageable by the said camming means and having a cam surface thereon engageable with the said cam surface on the sear, the said member being movable by the trigger bar in a direction transverse of its reciprocatory movement to engage the sear and release the hammer and the said member thereafter engaging and moving the sear repetitively to release the hammer upon each reciprocation while the trigger remains in pressed position.

8. In an automatic pistol, the combination of a frame, a barrel, a slide automatically reciprocable upon firing, a hammer movable to cocked position by the slide upon recoil movement thereof, a sear for holding the hammer in cocked position and having its lower portion bifurcated with a cam surface thereon, a pivot pin for the sear, a longitudinally movable trigger and trigger bar, and two separately movable closely adjacent members immediately beneath the slide and each having its lower portion extending between the sear bifurcations and each having an opening therein through which the sear pivot pin extends which opening is of suitable size to permit but limit movements of the member, one of said members being a disconnector having a portion initially interposed between the trigger bar and the sear to operatively connect them so that when the trigger is pressed the bar may move the sear to release the hammer, the said disconnector upon recoil movement of the slide

being moved thereby to a disconnecting position wherein the sear is free to return to its hammer engaging position independently of the trigger bar and the said disconnector being restored to its connecting position only upon release of the trigger and upon return of the slide to its forward position, and the other of said members having a cam surface thereon and being movable by the slide separately from the disconnector and engaging the cam surface on the sear repetitively to move the sear and thereby release the hammer without further movement of the trigger.

HORACE J. KENNEDY.
